UNITED STATES PATENT OFFICE.

WILLIAM J. RUFF, OF QUINCY, ILLINOIS.

PARACHUTE.

1,353,130.

Specification of Letters Patent. Patented Sept. 14, 1920.

Application filed May 25, 1918. Serial No. 236,459.

To all whom it may concern:

Be it known that I, WILLIAM J. RUFF, a citizen of the United States, residing at Quincy, county of Adams, and State of Illinois, have invented certain new and useful Improvements in Parachutes, of which the following is a specification.

This invention has for its object the provision of a device of the class named which shall be of improved construction and operation. The invention is exemplified in the combination and arrangement of parts shown in the accompanying drawings and described in the following specification, and it is more particularly pointed out in the appended claims.

In the drawings

Figure 1 is a top plan view of a parachute embodying one form of the present invention;

Fig. 2 is a vertical section on line 2—2 of Fig. 1;

Fig. 3 is a fragmentary sectional view showing a detail of construction; and

Figs. 4 and 5 are views similar to Figs. 1 and 2 respectively but showing a slightly modified form of the invention.

With the rapid development of aviation there has become apparent the need of something that will take the place that the life-boat occupies in navigation of the sea, and the parachute is the best solution that has so far been offered for this problem. Parachutes as heretofore constructed have been, however, uncertain in their action and unreliable. It is a comparatively easy matter to launch a parachute from a balloon which is free to move with the air currents, but it is much more difficult to launch a parachute from a balloon which is anchored so that there is a relative movement between the surrounding atmosphere and the balloon, and it is still more difficult to launch a parachute from a rapidly moving aeroplane. In order that a parachute may offer a reasonably dependable means of safety in case of accident to a balloon or an aeroplane, it is necessary that it shall be constructed so that there shall be certainty of operation when it is launched, so that it shall open quickly without waiting to fall a great distance, and so that it shall descend with a minimum degree of oscillation. The parachute should also be constructed so that it will afford the largest possible sustaining power for a given area of cloth, so that it may be adjusted to

meet various conditions of weight to be carried, and so that it may be under the control, as far as possible, of the person supported by it.

In the invention as illustrated in the drawings, a number of changes have been made over the old form of parachute, and the relation of these changes to the various requirements of modern aeronautics will be pointed out in connection with the description of the drawings. Referring to Figs. 1 and 2, the dome 10 of the parachute is made up of a series of sections of cloth 11 properly shaped and fastened together along seams 12. There is an opening 13 at the center of the dome which is surrounded by a ring 14 to which the inner ends of the sections of cloth 11 are attached. Extending downwardly from various points around the periphery of the dome 10 are flexible members 15 which may be cords but which are preferably flat tape or webs which continue past the periphery of the dome of the parachute and are sewed to the connected edges of the sections 11 along the seams 12, and have their upper ends connected to the ring 14. Thus the tapes 15 form binders to reinforce the seams 12 and extend continuously from the ring 14 over the dome of the parachute past the edge of the dome and down to a ring 16 which is suspended beneath the parachute and to which all the tapes 15 are attached. Each tape 15 is provided with a buckle 17 by which the length of the tape may be accurately adjusted. Extending downwardly through the center of the parachute from the ring 14, and connecting the ring 14 with the ring 16, are a number of cords 18 which are also preferably flat webs or tape like those shown at 15. The weight to be carried by the parachute may be suspended from the ring 16 in any suitable manner, and in the drawing a series of straps 19 are shown attached to the ring 16 in a manner to support a ring 20 from which a safety hook 21 is suspended, which may be secured to the belt of the aviator. Of course other means may be employed for sustaining the weight of the person descending in the parachute. Fig. 3 shows a slight modification in which the webs 15 instead of being attached directly to the ring 16 are provided with small rings 21' which slide on the straps 19 attached to the ring 16 for suspending the lower ring 20.

In operation, the parachute is carefully

folded and stored in a properly constructed carrier such as is used for the purpose by aviators, and arranged so that when a person's weight is suspended from the hook 21 5 the parachute will unfold and be discharged from its container. The use of flat webs or tape is advantageous in this launching operation for the reason that they will fold upon one another more readily than cord or 10 rope and do not have the same tendency to snarl and tangle. It is well in folding the tape to place a fold of newspaper or similar material between the folds of tape, as this assists in preventing the tape from becoming 15 tangled. When the parachute is launched from its container, the weight of the aviator is first transmitted to the dome or cloth portion through the cords 18, thus drawing the central portion of the dome 20 downwardly at the very beginning of the descent. As the central portion of the dome is thus drawn through the air in a downward direction, the periphery immediately catches the air and tends to turn back and 25 out. If it were not for the cords 15, the parachute would be immediately turned inside out before the aviator had descended more than a very few feet, and the first part 30 of this process is what actually takes place, but when the process has proceeded to the point where the parachute is in its open position, it is arrested by cords 15 and the air immediately fills the dome of the parachute which is now open and in position to 35 sustain the weight of the operator before the operator has fallen any appreciable distance, and consequently before the weight has attained any considerable momentum. Thus a positive opening action is imparted 40 to the parachute, like that by means of which an umbrella is opened when the handle is drawn downwardly through the ferrule attached to the ribs. The surrounding atmosphere pushes up on the periphery of the parachute like the braces for the 45 ribs push upwardly on the periphery of the umbrella.

This operation differs in many respects 50 from that of a parachute which has the sustaining cords attached to the periphery only, for in the old form of parachute, the weight of the operator as he descends through the air, has a tendency to draw the periphery of the parachute inwardly and the central portion trails behind, so that he 55 ordinarily falls through the air a great distance before the resistance of the small amount of air caught by the lower edges of the parachute becomes great enough to force 60 the periphery of the parachute outwardly and cause it to open, and when the parachute has finally opened, the rate of descent has become so great that the parachute is subjected to excessive strains in overcom- 65 ing the momentum which has been de-

veloped; thus a much larger and heavier parachute is required than is necessary where the parachute is constructed so that it will open immediately after it has been launched.

70

The smaller parachute has a great advantage aside from the difference in weight which must be carried, because it is much less liable to be struck by falling bodies from above and affords a smaller target for 75 the fire of an enemy. It will also permit more rapid descent with safety after it has once opened, and this of course is also a great advantage in warfare.

75

With the old form of parachute, the 80 amount of spread depends to some extent upon the weight sustained, for the reason that the weight tends to draw the periphery of the dome inwardly, so that a heavier person would have in fact less sustaining area 85 when suspended by a particular parachute than a lighter person would. In the present form, the weight is suspended partially by the cords 18 and partially by the cords 15, so that it is distributed over the entire 90 spread of cloth, and the amount the parachute is opened may be regulated by the buckles 17. In this way the parachute may be accurately adjusted so as to give the best results for a given weight to be sustained, 95 and it is consequently not necessary to provide extra spread of cloth, but each parachute may be accurately adjusted to give the maximum sustaining power and minimum spread for the particular weight it is to 100 carry. This, of course, helps to decrease the amount of weight necessary for the aviator to carry, decreases his risk of being struck during descent, and makes it possible to provide for the most rapid rate of descent compatible with safety.

105

It is desirable to provide an opening 13 in the dome of the parachute as this tends to decrease the oscillation during the descent, but in the old form of parachute this 110 opening permitted the escape of air from within the folds of the parachute at the beginning of a descent and thus had a tendency to form a vacuum within the folds and prevent the folds from opening. This difficulty is overcome in the present form for the reason that the central portion of the dome is drawn downwardly at the beginning of the descent and the parachute is positively opened before this action of the air 120 occurs.

115

In the form of the invention shown in Figs. 4 and 5, a pair of envelopes or domes 25 and 26 are employed in place of the single dome as in the form already described. 125 The lower or inner dome 25 is shown in elevation in Fig. 5 while the upper dome 26 is shown in section. This form of the invention differs from the one previously described only in the addition of the dome 26 130

which is connected with the dome 25 by a series of tapes 27 adjustably connected with the periphery of the dome 25 by buckles 28 connected with the tapes 15 at the points 5 where they join the cloth of the dome 25. The additional dome 26 decreases the total diameter of the parachute required for the given weight quite materially, and also has a very appreciable stabilizing effect to prevent 10 oscillation during descent. As the parachute tends to swing from one side to the other the direction of the current of air through the opening 13 in the lower parachute changes, so that the upwardly moving air impinges upon the upper dome in a direction to correct the swaying tendency of the parachute. It will be noted that the connecting tapes 27 may be adjusted so as 15 to space the upper dome from the lower one 20 the proper distance to obtain the best results.

I claim:

1. In combination, a flexible member arranged to form when opened the dome of a parachute, a device for supporting a weight 25 to be carried by said parachute, cords extending from said supporting device to the central portion of said flexible member, supplemental cords extending from said supporting device to the periphery of said flexible member, and means for adjusting the 30 length of said last-mentioned cords.

2. In combination, a flexible member arranged to form when opened the dome of a parachute, said flexible member having an 35 opening at the central portion thereof, weight-sustaining cords connected with said flexible member near the central portion thereof, and supplemental cords connected with the periphery of said flexible member 40 to limit the upward movement of said periphery.

3. In combination, a flexible member arranged to form when opened the dome of a 45 parachute, and flat tape connected with said flexible member and arranged to form the sustaining cords of said parachute.

4. In combination, a flexible member arranged to form when opened the dome of a 50 parachute, and sustaining cords for said parachute comprising flat webs or tape extending from the central portion of said flexible member past the periphery thereof and downwardly to a position to sustain the weight to be supported by said 55 chute.

5. In combination, a parachute comprising a dome or sustaining portion having an opening at the center thereof, sustaining

60 cords extending downwardly from the central portion of said dome, a supporting ring carried by said sustaining cords, supplemental cords connected with the periphery of said dome and having their lower ends attached to said supporting ring, and means for adjusting the length of said supplemental cords.

6. A parachute comprising two flexible members arranged to form when opened two air-engaging domes arranged one above the other and means for adjustably connecting 70 said domes together.

7. A parachute comprising two flexible members arranged to form when opened a pair of domes positioned one above the other, the lower dome having a central opening therein, means for adjustably connecting the peripheries of said domes, and means for connecting the central portion of one of said domes to the weight to be carried by said parachute.

8. A parachute comprising two flexible members arranged to form when opened a pair of domes positioned one above the other, means for connecting the peripheries of said domes, means for connecting the 85 periphery of the lowermost dome to the weight to be carried by said parachute and means for connecting the central portion of said lowermost dome to said weight.

9. A parachute comprising a canopy made 90 of flexible material and unprovided with stiffening ribs, flexible weight-supporting means secured to said canopy near the central portion thereof, flexible members secured to the periphery of said parachute and 95 connected at their lower ends with said weight-supporting means, and means in each of the flexible members for adjusting the length of the latter.

10. A parachute comprising a canopy 100 composed of flexible material foldable transversely to the radial lines of said canopy, flexible cords secured to said canopy near the central portion thereof and extending downwardly therefrom, the lower ends of 105 said cords being secured to a weight-supporting device, and flexible cords extending from the periphery of said parachute to said weight-supporting device, each flexible cord being arranged for adjustment in length 110 independently of the other flexible cords.

In testimony whereof I have signed my name to this specification on this 22d day of May, A. D. 1918.

WILLIAM J. RUFF.
